CATCH WITH ASSEMBLED SPRING

Benjamin H. Matthews, Chagrin Falls, and Galen L. Larimore, Cleveland, Ohio, assignors to The Langenau Mfg. Company, Cleveland, Ohio, a corporation of Ohio

Application July 8, 1954, Serial No. 442,169

2 Claims. (Cl. 292—128)

This invention relates generally to hardware and more particularly to latches and the like.

An object of this invention is to provide a latch in which all parts may be prefabricated before use and then quickly and easily assembled for use.

Another object of this invention is to provide a latch which is constructed of standardized sections which can be assembled by snapping the respective sections together in such a manner that they cannot be disassembled without the use of special equipment.

A further object of this invention is to provide a pivotal latch which may be readily assembled without the use of special tools.

A still further object is to provide a pivotal latch which may be finally assembled without the use of any tools whatsoever.

Another object of the present invention is to provide a latch characterized by its structural simplicity, the ease of assembly of its parts, its strong and sturdy nature and its low manufacturing cost. Other features of this invention reside in the arrangement and design of the parts for carrying out their appropriate functions.

Other objects and advantages of this invention will be apparent from the accompanying drawings and description and the essential features will be set forth in the appended claims.

In the drawings,

Fig. 1 is a sectional view through one embodiment of the improved latch and a coacting catch mounted in the walls of a lid and base respectively of a box with the latch in its latching position but not engaging the catch;

Fig. 2 is an enlarged top plan view of the latch taken along the plane of line 2—2 of Fig. 1;

Fig. 3 is an enlarged vertical elevational view of the latch taken along the plane of line 3—3 of Fig. 1;

Figs. 4, 5 and 6 are enlarged central sectional views disclosing the movements required in assembling the latch member into the aperture of the anchoring plate, oscillatory about its pivot pin.

Although the present invention may be applied in many ways, it has been chosen to illustrate it in connection with the lid and base walls of a box.

The latch generally shown at 10 is mounted in a recess 11 of the wall 12 carried by the box lid and is adapted to engage a catch shown at 14 in Fig. 1. The catch 14 is provided with screw threads 14a on its periphery which are adapted to secure it in the base wall 15 of the box. The catch is provided with annular flanges 14b in its bore for engagement by the depending hook shape portion of latch 10.

The latch 10 includes an anchoring plate 16 secured to the wall 12 by screws 17 or other fastening means passing through chamfered screw openings in the plate 16, as seen in Fig. 3. The anchoring plate 16 is stamped or provided from sheet material and may have any suitable peripheral form. A rectangular opening 16a is provided in the anchor plate to receive a shield member

2

18 therein. The shield member 18 may be cut or stamped from a single sheet of material and bent in substantially U-form, as illustrated in Fig. 3. The shield member 18 is provided with tab members 18a which extend upwardly through anchor plate 16 on opposite sides of aperture 16a. Shoulder stops 18b and locking ears 18c are provided on the shield member 18 to retain the shield member in a desired position upon the anchor plate 16. The tab members 18a are provided with aligned openings which receive a transversely extending pivot pin 20.

A latch member is normally carried by the anchor plate 16. The latch member is generally L-shape and has a uniform thickness. It consists mainly of three portions 21, 22 and 23 as defined by the dot-dash lines of Fig. 6. The first portion 21 forms a pivot for oscillating the latch and includes that zone defined generally by the apex or intersection of the two legs of the L. The second portion 22 includes the catch engaging hook 24 which extends downwardly through the aperture 16a between the side walls of shield 18 to a zone below the anchor plate 16 where the hook 24 engages the lower annular flange or rim 14b in the catch 14. In general, it is that leg of the L which extends below the anchor plate 16. The third portion 23 includes that leg of the L which lies above the anchor plate 16 and has a handle 25 attached to its end. The handle 25 protrudes from the recess 11 to a point beyond the wall 12 so as to facilitate manual operation of the latch member. The handle 25 may be of any suitable shape. It may even be an extension of the part 23.

Fig. 4 clearly shows the central portion of the latch member wherein the first portion 21 is located between the second and third portions 22 and 23 respectively. An extension 26 is provided at this zone and contains a notch or cutout 27 in the general shape of a half circle therein. Upper and lower shoulders 28 and 29 respectively are formed on opposite sides of the notch or cutout 27. These shoulders play a very important part in the pivotal mounting of the latch member. The upper shoulder 28 engages a substantial portion of the upper circumferential surface of the pin 20, as shown in Figs. 1 and 6. This shoulder is a pivoting projection at the junction of the upper and lower legs of the L-shape latch member and serves as a fulcrum on the pivot pin 20 as the latch member is moved from a latching to a non-latching position, by movement of handle 25. The lower shoulder 29 is substantially shorter than the upper shoulder 28 and serves as a retaining means to keep the latch confined to the pivot pin 20 during its pivotal movement. Together the upper and lower shoulders envelop substantially half or slightly more of the circumferential surface of the pivot pin 20. Shoulder 29 prevents any tendency to lift the extension 26 off of the pin 20 in a generally vertical plane. It should be noted that the bottom of shoulder 29 is sloped at 30 to intersect the second portion 22 of the latch member. The purpose of this construction will be more fully described hereinafter. In order to prevent the latch from sliding away from the pin 20 in a horizontal direction, resilient means is provided operatively connected between the latch member and the tabs 18a. In the present disclosure, it takes the form of spring 32, as best illustrated in Figs. 4 through 6. The spring comprises generally an elongated straight leg portion 32a which is permanently fastened to the third portion 23 of the latch member at a point 32c adjacent the handle 25. The other end of the spring 32 is bent downwardly and partially back upon itself to form a hooked anchor end 32b. The elongated leg portion of the spring extends from the point 32c where it is secured to the latch, along and spaced from the top

65
60
70

surface of the latch member in the direction of notch 27. The spring 32 begins to curve into the hooked end at a point substantially above the upper shoulder 28 and continues to curve downwardly to a point slightly below the lower shoulder 29, as seen in the position of Fig. 5. It should be noted that the hook portion of the spring 32 lies a spaced distance beyond the notch 27 and shoulders 28 and 29.

When assembled, as shown in Figs. 1 and 6, the hooked end of the spring extends around the tabs 18a to a point where the distal end of the hook portion engages the intersection of the ends of tabs 18a and the upper surface of the anchor plate 16. The latch member is prevented from being horizontally displaced from the pivot pin 30 by spring 32 which anchors itself upon the tabs 18a and prevents horizontal movement of the latch member. The spring further acts to normally urge the upper leg of the latch downwardly toward the top surface of the anchor plate 16. The downward force created by spring 32 results from biasing its hooked end 32b during assembly. It will be seen in Fig. 5, as the hooked end 32b is forced downwardly over the tabs 18a the hook is spread open or enlarged and becomes biased and strained. In attempting to resume its normal position, a downward force is exerted upon the third portion 23 of the latch member causing it to normally assume a latching position. It should be further noted that the distal end of hook 32b engages the tabs 18a at a point below the center line of the pivot pin 20. This construction adds a factor of safety by insuring that the hooked end 32b will not slip over the top of tabs 18a during use. The anchor plate 16 also provides a convenient abutment for the distal end of hook 32b, when the spring becomes tensioned, as the latch member is raised to a non-latched position. The extent to which the latch may be raised is limited by the edge 22a of the second portion 22 of the latch member, as seen in Fig. 6, engaging the end of aperture 16a.

It should be understood that pin 20 is permanently assembled (as by riveting) in the tabs 18a before assembly of the other parts. This attachment of pin 20 is easily made by use of the proper tools after part 18 is connected to anchor plate 16.

To assemble the latch for operation, the tabs 18a are inserted into the rectangular aperture 16a until the stop shoulders 18b of the shield 18 come into contact with the bottom surface of anchor plate 16. The locking ears 18c are then bent over tightly against the upper surface of anchor plate 16. The shield member is thus held in place. Pivot pin 20 is permanently assembled between the tabs 18a. The latch member (including attached spring 32) is easily assembled into the aperture 16a of the anchor plate 16 by following the sequence of operation shown in Figs. 4, 5 and 6 of the drawings. First, the latch member is rotated counterclockwise until it assumes the position shown in Fig. 4 whereupon the catch engaging hook 24 of the second portion 22 is lowered into the aperture 16a. Second, the latch member is rotated clockwise until it reaches the position shown in Fig. 5 wherein the second portion 22 of the latch is lowered into the aperture 16a. The hooked end of spring 32 now abuts the upper edge of tabs 18a, as seen in Fig. 5. Further downward pressure is then applied to the upper surface of the third portion 23 of the latch member, as indicated by the vertical arrow of Fig. 5. By thus pressing the latch member downwardly, initial tension is placed upon the spring 32, because of the bias given to the hook portion 32b as it slides downwardly along the outer end of tab 18a. Continued pressing causes the lower shoulder 29 to abut the upper surface of pivot pin 20, whereupon a slightly greater pressure must be exerted to cause the spring to give just enough for the latch member to shift horizontally to the right from the position in Fig. 5, whereupon the sloping lower surface 30 of shoulder 29 will cam the shoulder 29 to clear the pin 20 and the pin will then snap into the notch 27 under the influence

of a strong retractive force from spring 32, and assume the final operative position shown in Fig. 6.

The latch is now permanently assembled and merely reversing the above procedure will not result in the disassembly of the latch. This is necessarily true because the lower shoulder 29 has a very sharp outer edge at the point of the intersection of notch 27 and the sloping undersurface 30. This edge does not furnish the wedging action in disassembly, as did the sloping surface 30 during assembly. Therefore, a vertical thrust of the same degree, but in the opposite direction of that used in assembling the latch member will not disassemble the latch. The pivot pin 20 must first be removed before the latch can be disassembled.

It should be apparent that the latch can be readily and quickly assembled without special tools. Assembly costs are low because the parts are easily snapped together without need of skilled help. The operation of this latch is similar to any conventional latch. When lid 12 is dropped, the rounded lower cam surface on the catch engaging hook 24 engages either the upper or lower flange or lip 14b in catch 14 to swing the latch member counterclockwise from a latching to an unlatching position until the hook member clears the annular flange and aligns with the bore of the catch 14. The spring 32 then rotates the latch member clockwise about pivot pin 20 into a latching position. The hook 24 engages the upper flange 14b if it is desired that the lid be only partially closed, and the lower flange if a tight seal between the lid and base is desired. For unlatching, the handle 25 is forced upwardly or in a counterclockwise direction, as viewed in Figs. 1 and 6, against the bias of spring 32. This action pivots the latch member around the fulcrum provided by the upper shoulder 28 and pivot pin 20, whereupon the catch engaging hook 24 clears the annular flange 14b so that the box lid can be raised.

In view of the foregoing description, taken in conjunction with the accompanying drawings, it is believed that a clear understanding of the construction, operation and advantages of the device will be quite apparent to those skilled in this art.

It is to be understood, however, that even though there is herein described a preferred embodiment of the invention, the same is susceptible to certain changes fully comprehended by the spirit of the invention.

What is claimed is:

1. In a latch adapted to engage a catch with said latch including an anchoring plate having an aperture therethrough, including a latch member movable between latching and unlatching positions and having a first portion forming pivotal means for oscillating said latch, a hook-shape catch engaging portion on a second portion of the latch member located on the catch side of said aperture extending swingably through said aperture and having a handle on a third portion of the latch member located on the opposite side of said aperture for pivoting said latch member, and including two tab members spaced on opposite sides of said aperture extending upwardly from said anchoring plate; the combination of a pivot pin extending between said tab members, an extension on said first portion between said second and third portions, said extension having a pivotal notch cut out, said notch formed by two shoulders on said extension, said latch member positioned with the extension between the spaced tab members, said shoulders being spaced apart a distance slightly in excess of the thickness of said pivot pin and straddling said pivot pin to permit oscillation of said hook portion, spring means operatively connected between said latch and said tabs, said spring comprising a generally straight leg portion and a hooked anchor end portion, said hooked portion extending spacedly around said tab members and engaging said tabs on the side of said pivot pin opposite that engaged by said pivotal notch and yieldingly constraining said latch against said pin, said

straight arm portion normally urging said third portion toward said retainer plate, and said hook portion to a latched portion, the upper of said two shoulders being longer than the lower shoulder, the lower shoulder being provided with a cam surface whereby said latch may be oscillated in one direction to engage said hooked anchor end of said spring with said tab and then oscillated in the opposite direction allowing said cam surface of said lower shoulder to slide over said pivot pin, said pivot pin thereby snapping into said notch, disassembly being impossible without removal of said pin.

2. In a latch adapted to engage a catch with said latch including an anchoring plate having an aperture therethrough, including a latch member movable between latching and unlatching positions and having a first portion forming pivotal means for oscillating said latch, a hook-shape catch engaging portion on a second portion of the latch member located on the catch side of said aperture extending swingably through said aperture and having a handle on a third portion of the latch member located on the opposite side of said aperture for pivoting said latch member, and including two tab members spaced on opposite sides of said aperture extending upwardly from said anchoring plate; the combination of a pivot pin extending between said tab members, an extension on said first portion between said second and third portions, said extension having a pivotal notch cut out, said notch formed by two shoulders on said extension, said latch member positioned with the extension between the spaced tab members, said shoulders being spaced apart a distance slightly in ex-

cess of the thickness of said pivot pin and straddling at least half the circumference of said pivot pin to permit oscillation of said hook portion, spring means extending from said third portion along the top surface of said latch toward said tabs, said spring comprising a generally straight leg portion and a hooked anchor end portion, said straight leg portion being fastened to said latch member along the top of said third portion, said hooked portion extending around said tab members and engaging said tabs on the side of said pivot pin opposite that engaged by said pivotal notch and yieldingly constraining said latch against said pin, said straight arm portion normally urging said third portion toward said retainer plate, and said hook portion to a latched position, the upper of said two shoulders being longer than the lower shoulder, the lower of said two shoulders being provided with a cam surface, whereby said latch may be oscillated in one direction to engage said hooked anchor end of said spring with said tab and then oscillated in the opposite direction allowing said cam surface of said lower shoulder to slide over said pivot pin, said pivot pin thereby snapping into said notch, disassembly being impossible without removal of said pin.
